UNITED STATES PATENT OFFICE.

MARSHALL D. GIBSON, OF WEBSTER GROVES, AND MILTON LANDIS OGLESBY, OF ST. LOUIS, MISSOURI, ASSIGNEES TO SAID GIBSON AND WILLIAM H. McCORMICK, OF ST. LOUIS, MISSOURI.

WRAPPING-MACHINE.

1,190,283.

Specification of Letters Patent. Patented July 11, 1916.

Application filed February 15, 1915. Serial No. 8,177.

To all whom it may concern:

Be it known that we, MARSHALL D. GIBSON and MILTON LANDIS OGLESBY, citizens of the United States, residing, respectively, 5 at Webster Groves and St. Louis, Missouri, have invented new and useful Improvements in Wrapping-Machines, of which the following is a specification.

This invention relates to wrapping machines, and more particularly to machines 10 for wrapping cubic or prismoidal articles or objects which are substantially rectangular but have portions more or less irregular and varying in shape, such for example, as 15 loaves of bread and the like, the contours of whose tops or portions which rise above the pans in which they are baked vary considerably.

The invention has for its objects to produce 20 a simple and inexpensive machine of the character above described by the use of which the articles can be wrapped tightly and effectually sealed notwithstanding irregularities and variations in size and shape; 25 to produce a machine which is capable of adjustment to suit articles of different sizes; and to attain certain advantages which will hereinafter more fully appear.

The invention consists in the parts and in 30 the arrangements and combinations of parts hereinafter described and claimed.

In the accompanying drawings wherein is illustrated an adaptation of the invention,— Figure 1 is a front elevation of the machine; 35 Fig. 2 is a section taken on or about the line 2—2 of Fig. 1; Fig. 3 is a view in section on an enlarged scale, the line of section being taken at right angles to that of Fig. 2, and approximately through the middle of the 40 machine, the movable parts being in the positions they respectively assume at the completion of the folding operation; Fig. 4 is a fragmentary detail view, partly in section, showing the mounting of the operating shaft 45 and gearing for the side end-folders; Fig. 5 is a section on the line 5—5 of Fig. 4; Figs. 6 to 13, inclusive, are schematic views showing progressive stages of the folding operations upon the wrapper.

50 The machine as illustrated in the draw-

ings includes a base member or frame 1, comprising an elongated middle portion, near the ends and on opposite sides of which, are alined lateral extensions 2. In other words, the piece is substantially H- 55 shaped. The middle portion and lateral extensions are of channel section, the flanges being disposed downwardly. At the ends of the lateral extensions 2 are ears 3 which are perforated to receive securing bolts 4 by 60 which the base member is secured to a supporting stand or table, which latter, of itself, forms no particular part of the present invention, and may be of any suitable construction. As shown in the drawings, the 65 stand comprises parallel horizontal channel members 5 which are mounted on uprights 6. The uprights may also be made of channel or angle section and suitably braced with respect to each other and to the horizontal 70 members.

The base member 1 is provided on top and bottom with alined bosses 7 and 8, respectively, with vertical bores therethrough to receive reciprocatory bars 9, there being 75 preferably four of these arranged in rectangular relation. Secured on the upper ends of the bars 9 is a skeleton frame 10 of substantially H-shape, the same being suitably stiffened by ribs 11. Interposed on the bars 80 9, between the bosses 7 of the base member and the frame 10, are loose sleeves 12 of rubber or other suitable cushioning material on which said frame 10 rests in its lowered position as will presently appear. The bars 85 9 are further provided with fixed collars 13 below the base member 1, said collars being arranged so as to rest on a vertically-movable actuator plate 14 to support the frame 10 in raised position, said actuator plate 90 having openings extending through downwardly-disposed bosses 15 thereon and through which the bars 9 slide. Extending up through a slot 16 in said actuator plate and pivotally secured between two ears 17 95 on the top thereof is a link 18. The lower end of this link is placed between and pivotally secured to the end portions of a pair of lever arms 19, the latter being pivotally mounted at their opposite ends between two 100

of the uprights 6 at the front of the supporting stand, as at 20. The lever arms are pivotally connected by a link 21 with a treadle lever 22 which is pivotally mounted between two rear uprights 6 of the supporting stand. The treadle lever, and through it, the parts connected thereto, are yieldably held in normal raised position by a spring 23 which is secured at one end to the treadle lever and at its opposite end to the rear horizontal member 5 of the supporting stand.

10 Detachably secured on the frame 10 is a plate or table member 24 on which the article to be wrapped is supported. As shown, this plate is provided with downwardly-extending marginal flanges 25 which serve to strengthen it, while inwardly from the endmost flanges are transversely-disposed flanges 26 which are located so as to fit snugly against the inner sides of correspondingly-arranged lugs 27 projecting upward from the frame 10, there being lugs 28 provided adjoining the flanges 26 on the plate to engage the ends of said rib. By this arrangement the lugs 28 form with the flanges 26 pockets into which the lugs 27 fit so as to prevent longitudinal and lateral displacement of the plate. The plate is provided at its middle with a boss 29 through which extends a countersunk hole in line with a screw-threaded hole extending through a boss 30 in the frame 10 so as to receive a securing screw 31. In this way provision is made for the interchange of plates of different sizes.

15 At the ends of the plate 24 are arranged angle pieces 32 which are preferably movably attached so as to be adjusted lengthwise of the plate. As shown the horizontal portions of the angle pieces are slotted, as at 33, and securing screws 34 are inserted through the slots into the plate 24. The upturned portions 32^a of the angle pieces 32 are rounded off somewhat pointedly, as best shown in Figs. 2 and 6, for a purpose which will later be set forth.

20 Mounted on the cross arms 2 of the base member 1, on opposite sides of the vertically movable article-supporting table just described, are vertically-disposed side plates 35 whose inner faces are plain, but on whose outer faces are provided stiffening ribs 36 which merge at their lower ends with horizontal base flanges 37. The base flanges are perforated to receive securing bolts 38 which are carried through slots 39 provided therefor in the cross arms 2 of the base frame 1. The bolts are secured by nuts 40, but with 25 sufficient looseness to allow the side plates to be moved toward and away from each other. To effect the adjustment of the side plates and to hold them in adjusted position, a screw 41, having right and left hand threaded portions 42, 43, is arranged so as

to engage counterpart threaded portions 44, 45, respectively, on said side plates. The screw is held from endwise movement by having a collar 46 thereon inserted between a pair of lugs 47 on the middle portion of 70 the base member 1, said lugs 47 being slotted to provide a bearing seat for the screw. A handwheel or other suitable handle 48 may be provided at either or both ends of the screw, as desired. Obviously, by rotating 75 the screw the side plates will be moved toward or away from each other, depending upon the direction of rotation.

At the tops of the side plates are outwardly and upwardly inclined extensions 80 or brackets 49 on which are secured oppositely-disposed plates 50, 51, said last-mentioned plates extending on opposite sides of said side plates. The lower edge portions of the plates 50, 51, are beveled in the region 85 of the side plates 35, as at 52, so as to be flush with the vertical inner faces of said side plates. The two inclined plates 50, 51, form with the vertically-movable article-supporting plate 24 which, in normal raised 90 position, occupies a position slightly below the lower edge portions of said plates 50, 51, a trough-like affair in which the sheet of wrapping paper is initially placed. This arrangement embodies one of the salient 95 features of the invention, namely, the provision of means for first giving to the sheet of wrapping paper a shape which will facilitate the formation of the successive folds of the wrapper with regularity and uniformity.

100 The wrapper blank or sheet, indicated generally by the letter A, is placed in the trough so as to be disposed equally both sidewise and endwise with respect to the middle of the article-supporting plate 24, the wrapper being laid loosely at first and resting at its middle on the upturned portions 32^a of the angle pieces 32. The article to be wrapped—in the drawings, a representation of a loaf of bread upside down—is placed on the supporting plate 24 thereby depressing the wrapper between the members 32^a, drawing the wrapper snugly to the loaf, and causing the middle of the end portions to pucker upwardly, as at a with oppositely pucker portions b on either side thereof at the corners. With the wrapper in this shape, the plate 24 is lowered, causing the wrapper to be drawn up close about 110 the lower portion of the loaf transversely thereof. During the downward movement of the plate 24, the upstanding portions 32^a of the angle pieces 32 travel in close proximity to end-plates 53 which engage the 115 pucker portions a of the wrapper so as to further fold the same up closer to the ends of the loaf. The top edges of these plates 53 are rounded off or crowned, as at 53^a to avoid tearing the wrapper. Said 120

115

120

125

130

plates are slightly narrower than the space between the side plates 35, and they are mounted so as to be adjusted to correspond to the adjustment of the angle-members 32 for loaves or other articles of different lengths. The particular mounting of these plates will be presently described with more particularity.

When the supporting plate has reached its lowermost position, the loaf will have been moved down entirely below the lower edge portions of the plates 50, 51, so that the side portions of the wrapper assume a vertical position, while the end portions which were initially puckered as at *a* and *b* are folded respectively close to the end of the loaf and to the adjacent upstanding side end portions *c* of the wrapper as shown in Figs. 9 and 10. After the folds have reached this stage the side end portions *c* are folded in against the plates 53 in a manner and by means now to be described.

Carried by the side plates 35 are side end folders 54. These comprise wings or plates having angularly-extending lugs 55 which are secured tightly on vertical shafts 56. The shafts are journaled in extensions 57, 58, of bracket members 59 which are secured on the outer faces of the side plates 35. These bracket members have horizontal slots 60 through which retaining screws 61 are inserted into the side plates so that the wings or folders 54 can be adjusted to suit the adjustment of the angle pieces 32 and plates 53. To facilitate this adjustment the retaining screws 61 are fitted with just sufficient looseness to allow the bracket members 59 to move easily, and the pair of oppositely-disposed bracket members on each side plate are provided with lugs 62 having right and left hand screw-threaded horizontal holes to receive the correspondingly-threaded end portions of a screw 63. This screw is journaled through openings provided therefor in the vertical ribs 36 of the side plate, and it has a collar 64 fixed thereon and fitted between bosses 65 provided on the inner faces of said ribs 36 so as to prevent endwise movement of the screw, said collar being provided with a milled or knurled wheel 66 by which the screw may be easily manipulated. By this arrangement it is only necessary to rotate the screw to effect the adjustment of the members 59 inwardly and outwardly, the screw holding them in position after the desired adjustment is attained.

The lower extensions 58 of the members 59 whose end portions are turned downward as at 67 have bearing collars 58 rotatably fitted therein. Said bearing collars are provided at their ends with thrust shoulders and have square axial openings through which extend the end portions of a crank shaft 69 which is also of square section, by which arrangement the shaft is afforded a

rotatable bearing and at the same time adjustment of the bearing endwise of the shaft is permitted. Bevel gears 70, also having square openings therethrough, are arranged on the crank shaft 69 so as to rotate therewith, but being slidable lengthwise thereof adjacent to the bearing collars 68, said bevel gears meshing with similar gears 71 on the lower ends of the folder shafts 56, the arrangement of the coöperating gears being such that they are maintained in proper relation at all times without interfering with the adjustments above set forth.

The two crank shafts, there being one on either side of the machine, have crank portions 72 in which are pivotally secured the upper end portions of actuator rods 73. These rods hang loosely from said cranks 72 through slotted or bifurcated lateral extensions 74 of the actuator plate 14 and they are provided with stop-collars or enlargements 75, 76, respectively, above and below the actuator plate, said collars being relatively arranged so that the plate engages them alternately during its reciprocation, and whereby the crank shafts are oscillated. The slotted or bifurcated extensions 74 are of sufficient length to permit the side plates 35 to be shifted with respect to each other without interfering with the coöperative relation of the rods 73 with the actuator plate.

As shown in the drawings, provision is made for the travel of the cranks 72 approximately through an angle of ninety degrees, which distance is distributed equally above and below a horizontal line through the axes of the shafts 69. Retractile springs 77 are connected at one end to loops 78 which are swiveled on the pivots from which the actuator rods 73 are suspended. The opposite ends of the springs are fastened to studs 79 projecting from the ribs 36 on the outside of the side plates 35 in same plane as the axes of the crank shaft, said springs being carried through vertically elongated openings 80 provided therefor in the side plates. By this arrangement the springs 77 complete the actuation of the cranks after the latter have been moved to either side of dead center by the engagement of the actuator plate with the collars 75 or 76 as the case may be.

In folding the side end or corner portions of the wrapper inward, the pair of folders or wings operating on one side plate are made to move in advance of those on the other side plate. That is, the wings on one side fold the corner portions *c* on the corresponding side of the wrapper in against the plates 53 and the other wings fold the opposite corner portions *c* of the wrapper in upon the first-mentioned wings. The wrapper folds have then reached the stage as illustrated in Fig. 11, in which form the

- wrapper extends all about and above the sides of the article. The folded over side end or corner portions *c* are next folded in upon the top of the article as at *d*, causing the adjacent portions of the sides of the wrapper to fold triangularly against the inner face thereof as at *e* leaving two up-standing flaps *f*. The mechanism for accomplishing this will now be described.
- 10 Hingedly mounted on angle brackets 81 at the opposite end portions of the base frame 1 are end folders which may be indicated generally by the numeral 82. These folders, as shown, each comprise a bell-15 crank having a flanged arm 83 and a bifurcated arm 84, said bell-crank being pivoted, as at 85, on a stud which is mounted on the side webs 86 of said angle bracket 81. Depending from between the bifurcated arm of the bell-crank 84 to which it is pivotally secured, is an actuator rod 87 which extends through a slotted or bifurcated extension 88 at the end of the actuator plate 14. This rod has a 20 stop collar or enlargement 89 thereon beneath said actuator plate so as to be engaged by the latter as the same moves downward and thereby actuate the bell-crank as will presently be described.
- 25 30 Adjustably mounted on the arm 83 of the bell-crank, as by having a slot 90 therein through which securing bolts 91 project from said arm 83, is a flanged extension member 92 having an angularly-turned end portion 93. Hinged on a lug 94 at the end of the portion 93 is a forked member 95 which is provided with an opening through its web near the end which is attached to the lug 94. Extending through said opening and an opening in the member 92 in line therewith is a bolt 96 on which a spring 97 is sleeved between said members 92 and 95, and another spring 98 is interposed between the opposite side of the member 95 and a nut 99 at the end of the bolt. The springs 97, 98, serve to center the member 95 and permit it to yield in opposite directions to give flexibility to the end folder mechanism in order to compensate for irregularities in the contours of the top portions of the articles wrapped upon the machine.
- 35 Secured across the outer end portions of the forks 100 of the member 95 is a thin plate 101 having an offset outer portion 102 whose edge is rounded or crowned after the manner of the initial folder plates 53 so as not to tear the wrapper. This plate 101 is arranged so as to press against the outer lap of the infolded side portions *c* of the wrapper at the stage shown in Fig. 11 so as to turn said portions inwardly over the edge of the loaf or article being wrapped as the end folder moves into the position shown in Fig. 3. In this operation the fold 40 is partially effected. In other words, the

portions of the wrapper engaged by the plate 101 are pressed inward at such an angle approximating a horizontal that the fold may be readily completed by a wing plate 103 which is hingedly mounted on 70 the member 95 so as to engage the portion of the wrapper thus infolded at this stage with an inward and downward sweep whereby the wrapper is drawn endwise as well as pressed down against the top side of the 75 article.

As shown, the wing plate is bent or curved slightly so that its edge 104 may move to a plane below that occupied by the offset portion 102 of the plate 101 so as to press the 80 wrapper close upon the article and permitting the portion 102 to move over the edge portion of the article with sufficient clearance to avoid shearing or tearing the wrapper. The wing plate is carried by a member 105 which is provided with angularly-disposed legs 106 straddling the members 95 and 92, said leg portions being pivoted, as at 107, on lugs 108 extending upwardly from the forks 100 of the member 95 close to the 90 body portion of said member 105. The member 105 has a lug 109 projecting therefrom and to which is secured one end of a spring 110 whose opposite end is attached to a lug 111 projecting from the web of 95 the member 95, said spring being provided to complete actuation of the carrier of the wing plate with a quick snapping action when it has been moved in either direction past a dead central position with respect to 100 the axis of the pivot 107 and line of pull of the spring.

Normally, when the end folders are in the down position as shown in Fig. 1, and when traveling from that position to fold the 105 wrapper, the wing plate 103 sets away from the plate 101, while the legs 106, whose end portions have angular extensions or feet 112, project forwardly to a position so that they are brought against the side end or corner 110 folder wings 54 just about the time the edge of the portion 102 of the plate 101 engages the wrapper. The arrangement of the legs 106 is such that, being arrested by coming in contact with said folder wings 54, the 115 carrier 105 for the top folder wing plate 103 is caused to move with respect to the member 95 on which it is mounted, said member 105 being moved past dead center just after the plate 101 has been brought to rest with 120 its portion 102 overhanging the end of the article being wrapped. The spring 110 then snaps the wing plate 103 down against the top of the article and completes the folds of the wrapper to the stage shown in Fig. 12, in which stage the several folds are held 125 snugly in place by the several springs 77, 98, and 110 which respectively act upon the folder devices with which they are associated. As the end folders 82 move back to 130

normal position the legs 106 engage the end portions of the tripper bars 113; whereby the top folder wings 103 are thrown to normal position away from the plate 101, as shown in Fig. 1.

After the completion of the folds of the wrapper to the stage shown in Fig. 12, and while the several mechanisms are still in the relation they assume at this stage, the 10 standing flaps *f* of the wrapper are folded the one upon the other by hand, thus completing the wrapping, as shown in Fig. 13. The pressure on the treadle lever is then relieved, permitting the spring 23 to raise 15 the actuator plate through the medium of the links and levers connecting the latter with said treadle lever. After the supporting plate or table 24 has been restored to its normal elevated position the wrapped article 20 is removed therefrom and the wrapper may then be sealed in any desirable manner.

As the supporting plate 24 rises the several folder devices are withdrawn from engagement with the wrapper, the top end 25 folders 82 dropping by gravity, and being assisted at the start by the article pressing upwardly against the wing plate 103 and also by springs 114 carried by said end folders and engaging the angle-brackets 81; 30 while the side-end or corner folders 54 are swung back to normal position, after the article has been lifted high enough to disengage the flaps *c* from said folders 54, by the engagement of the actuator plate 14 with 35 the collars 75 on the rods 73 which in turn actuate the cranks 72 on the shafts 69. The continued upward movement of the supporting plate 24 disengages the wrapper from the initial folder plates 53, after which the 40 wrapped article is free to be removed from the supporting plate.

To adjust the end folders 82 to correspond with the adjustments of the other folders as hereinbefore set forth, the angle brackets 81 45 are provided with blocks or lugs 115 which project downwardly through slots 116 in the base frame 1 and are respectively provided with right and left hand screw-threaded openings to receive counterpart 50 threaded portions 117 of a screw 118. Said screw 118 has a collar 119 at the middle thereof engaged between two lugs 120 which are recessed as at 121 to provide seats for the screw. The screw is provided at either end 55 with a hand wheel 122.

To provide for the interchange of the initial end folder plates 53 to suit adjustments of the machine for wrapping loaves or articles of different widths, said plates are 60 attached to clips 123 which are detachably fitted to the upper edge portion of the vertical walls of the angle brackets 81. In this way several plates 53 may be made in different widths, but mounted on standardized 65 clips and provided in the equipment of the

machine, so as to be readily interchanged when it becomes necessary to adjust the side plates 35 toward or away from each other.

By the use of a machine as herein set forth, cubic or prismatical articles of irregular shapes, and more particularly loaves of bread, but without limitation thereto, may be wrapped neatly and tightly, and without materially increasing the cost of production of the article. And it is to be understood 70 that while the machine represented in the drawings illustrates a practical embodiment of the invention, many changes and modifications in the construction and operation of the parts may be made without departing 75 from the spirit of the invention, which comprehends broadly the idea of giving an initial form or set to the wrapper blank prior to the operation of the several devices which effect the successive folds. 80 85

We claim:

1. In a wrapping machine, a support for the article to be wrapped, and means for supporting the wrapper blank in relation to said article support, whereby, when the 90 article is placed on said support over the wrapper blank the latter is drawn close to the underside of the article and the wrapper is given an initial shape with its side portions deflected upwardly throughout its 95 length on opposite sides of the article and with its middle end portions puckered upwardly, thereby producing partial folds of said side and end portions of the wrapper.

2. In a wrapping machine, a support for 100 the article to be wrapped, a support for the wrapper blank on opposite sides of the article support, and supports for the middle end portions of the wrapper blank mounted adjacent to the ends of said article support, 105 whereby, when the article is placed on the support over a wrapper blank the wrapper is given an initial shape with its side portions deflected upwardly throughout its length on opposite sides of the article and with its middle end portions puckered upwardly, thereby producing partial folds of 110 said side and end portions of the wrapper.

3. In a wrapping machine, a support for 115 the article to be wrapped, means for supporting the wrapper blank in relation to said article support, whereby, when the article is placed on said support over the wrapper blank the latter is drawn close to the under side of the article and the wrapper is given an initial shape with its side portions deflected upwardly throughout its length on opposite sides of the article and with its middle end portions puckered upwardly, and means for successively engaging the wrapper so formed for folding first the middle end portions thereof up to the adjacent ends of the article, then folding the side end portions inwardly the one over the other to said folded up middle portions, and finally fold- 120 125 130 135

ing the upper portions of the infolded side end portions inwardly upon the top of the article and producing upstanding flaps on opposite sides of the article.

- 5 4. In a wrapping machine, a vertically-movable support for the article to be wrapped, a support for the wrapper blank in coöperative relation to the article support, said second mentioned support being 10 arranged and adapted so as to deflect the wrapper upwardly on opposite sides of the article and to pucker the middle end portions of the wrapper upwardly when the article is placed on its support over the wrapper, means coöperating with said wrapper support and said article support during the 15 downward movement of the latter for engaging the puckered end portions of the wrapper to fold the same up close to the article and form side end flaps, means for folding said flaps inwardly the one over the other close to the folded up middle end portions of the wrapper, and means for folding the upper portions of the infolded side end flaps inwardly and down upon the 20 top of the article, and forming upstanding flaps on opposite sides of the article.
- 25 5. In a wrapping machine, a vertically-movable support for the article to be wrapped, oppositely inclined plates on opposite sides of said article support and constituting with the latter a support for the wrapper blank, means coöperating with said inclined plates adjacent to the ends of said article support for supporting the middle portion of the wrapper blank at an elevation above said article support, whereby, when the article is placed on the support over the wrapper blank the latter is drawn 30 close to the under side of the article and the middle end portions of the wrapper blank are puckered upwardly, end folder members located adjacent to the ends of the article support and adapted to engage 35 said puckered portions of the wrapper during the downward movement of the article support so as to fold the middle end portions of the wrapper up close to the adjacent ends of the article, and also forming 40 side end flaps, side end folders mounted adjacent to the ends of said article support, means for actuating said folders in timed 45 relation to each other and to said article support whereby the side end flaps are folded inwardly the one over the other close to said upfolded middle end portions of the wrapper after the table has come to rest, and end folders arranged and adapted to fold the upper portions of the infolded 50 side end flaps inwardly and downwardly upon the top of the article, and resilient means acting upon said folders to hold them yieldably in operated relation to the wrapped article.
- 55 6. In a wrapping machine, a supporting 60

base, a vertically-movable support for the article to be wrapped, means for supporting the wrapper blank in relation to said article support, said means including vertical plates mounted on said base on opposite sides of said article support and plates extending outwardly and upwardly from the tops of said side plates, means at the opposite ends of said article support for supporting the middle portion of the 70 wrapper blank initially above the article support, vertical end folder plates mounted adjacent to the ends of said article support in coöperative relation to said last mentioned wrapper supporting means, side end 75 folder wings hingedly mounted on said vertical side plates, means for actuating said wings in timed relation to the movement of said article support, end folders hingedly mounted on said base adjacent to said vertical end folder plates, said last mentioned end folders having resiliently-supported members pivotally mounted thereon, said members having means for initially engaging the wrapper to press the same inwardly 80 over the ends of the article, and spring-pressed members hinged thereon to engage said initially inwardly pressed portions of the wrapper with an inward and downward sweep to press the same down upon the 85 top of the article.

90 7. In a wrapping machine, a supporting base, a vertically-movable article support thereon, a support for the wrapper blank comprising upstanding members on said 100 base on opposite sides of said article support, upwardly and outwardly inclined members at the upper ends of said side members extending above said article support and beyond the ends thereof, and upwardly extending members at the ends of said article support, vertically-disposed initial end folder members in coöperative relation to said upwardly extending end members, side end folder members hingedly 105 mounted on said side members at opposite ends thereof, and final end folders hingedly mounted adjacent to said vertically-disposed initial end folders and having portions adapted to move over the end portions 110 of the article support, means for actuating said article support and the respective movable folders in timed relation, and means for adjusting all of said supports and folder devices with respect to said article support. 115

120 8. In a wrapping machine, a supporting base, vertical reciprocating bars slidably mounted through said base, an article-supporting table on the upper ends of said bars, a vertically-movable actuator member 125 slidably mounted on the lower portions of said bars, stops arranged on said bars to be engaged by said actuator member to support said article-supporting table in raised position, means for supporting the wrapper 130

blank comprising upstanding side members mounted on said base on opposite sides of said article-supporting table, upwardly and outwardly extending members at the upper 5 ends of said side members, members at the ends of said article-supporting table having upstanding portions for supporting the middle portion of the wrapper blank, upstanding initial end folder members mounted 10 in coöperative relation to said last-mentioned members, side end folder members mounted on vertical shafts at the ends of said side members, said shafts having bevel gears thereon, crank shafts on said side 15 members having bevel gears meshing with the bevel gears on said folder shafts, rods suspended from the cranks of said shafts, slidably engaging said actuator member, and having stops thereon above and below 20 said actuator member and located with respect to each other and to said actuator member so that the side folders on one side member move in advance of those on the other, springs arranged and connected to 25 said cranks so as to throw the cranks in either direction when moved past dead center, and final end folders comprising bell-crank members, rods depending from one arm of said bell-crank members, slidably 30 engaging said actuator member, and having stops below said actuator member, the opposite arms of said bell-crank members having outward angular extensions, members pivotally mounted on said extensions 35 and being spring-pressed on opposite sides, means at the ends of said last-mentioned members for initially engaging the wrapper to press the latter inwardly over the top of the article, wing members hingedly mounted 40 on said last-mentioned members and adapted to engage and press the inturned portions of the wrapper down upon the top of the article, tripper mechanism for actu- 45 ating said wing members in opposite directions, and springs for throwing said wing members in either direction when moved past dead center by said tripper mechanism.

9. In a wrapping machine of the character described, a support for the article to be wrapped, and a coöperating support for 50 the wrapper blank including means whereby the wrapper is given an initial shape with its side portions extending upwardly on opposite sides of the article and with its middle end portions puckered upwardly, 55 thereby producing partial folds of said side and end portions of the wrapper.

10. In a wrapping machine of the character described, a support for the article to be wrapped, a coöperating support for the 60 wrapper, one of said supports being movable with respect to the other and including means whereby the wrapper is given an initial shape with its side portions extending upwardly on opposite sides of the article 65 and with its middle end portions puckered upwardly, thereby producing partial folds of said side and end portions of the wrapper, and initial end folder members located adjacent to the ends of the article support 70 and in coöperative relation thereto and to said wrapper support so as to engage said puckered portions of the wrapper, whereby when the actuation of the movable support occurs the side portions and the middle end 75 portions of the wrapper are completely folded up close to the adjacent ends of the article and side end flaps are formed.

In testimony whereof, we have hereunto set our hands in presence of two subscribing 80 witnesses.

MARSHALL D. GIBSON.
MILTON LANDIS OGLESBY.
